AUTOMATIC FIREARM

Hanns Lippert and Erwin Hepperle, Zurich, Switzerland, assignors to Verwaltungsgesellschaft der Werkzeugmaschinenfabrik Oerlikon, Zurich-Oerlikon, Switzerland

Application June 27, 1946, Serial No. 679,599
In Switzerland July 6, 1945

4 Claims. (Cl. 89—33)

1

In certain types of automatic firearms the barrel together with the breech casing slides within a chamber or outer casing. This latter casing, in its turn, is mounted by easily detachable means on a base, for instance a cradle, or in the engine in the case of motor guns, etc. Besides housing the moving parts and connecting the weapon with its base, however, the outer casing serves other purposes, controlling in the first place the breech block locking operation by means of curved grooves, stops and similar elements with which it is equipped. Finally, the trigger mechanism, the trigger buffer springs and the ammunition feed frame are also fitted on the outer casing.

In newer designs, breech block mechanisms are to be found which are no longer controlled by means fitted in the outer casing, whereby one of the essential functions of such casing is eliminated.

The present invention relates to an automatic firearm in which, by taking into due consideration the fact that the outer casing no longer acts as breech block control means, a considerably simpler design is made possible. The automatic firearm according to the present invention is characterised by the feature that the outer casing, now merely designed as top slide bar of the breech casing, which latter glides with its bottom face directly on the cradle carries the trigger mechanism together with its buffer spring system, and the ammunition feed frame.

A frame for ammunition belt feed may be fitted on the trigger casing, or else a magazine may be inserted in the ammunition feed frame. The outer casing designed as top slide bar for the breech casing is suitably connected with the cradle.

The fact that the outer casing is now merely shaped as a slide bar makes a substantial reduction in the total weight possible, since—in view of the fact that trigger mechanism and ammunition feed frame are rigidly connected with the cradle—the weight of the moving parts can be reduced also.

The accompanying drawing shows in Figs. 1—5 two constructional examples of realisation of the present invention. In this drawing:

Fig. 1 is a longitudinal section through a firearm in which the ammunition feed is effected by a belt, schematically represented;

Fig. 2, a section along line II—II in Fig. 1, on an enlarged scale;

Fig. 3, a section along the line III—III in Figs. 1 and 4, on an enlarged scale with the breech block in its forward position;

2

Fig. 4, a section along line IV—IV in Fig. 3; Fig. 5, the firearm according to Fig. 1, with inserted magazine.

The barrel 1 is inserted in known manner, as by means of a bayonet joint, in the breech casing 2. The breech casing 2 slides by way of extensions 4 and 5 in corresponding guides 6 and 7 on the cradle 3. The sliding movement of the breech casing 2 on the cradle 3 takes place against the pressure of the spring 8 guided on a rod 9 and bearing at its rear end against the cradle 3, and at the other end engaging a lug 10 depending from the barrel 1 and projecting through the cradle guide 6.

Within the breech casing 2 is fitted the breech block 11. The principle of the breech block, not particularly described here, can be assumed to be that of gas-operated firearm of known type; it may also be a one-piece breech block, locked by stored-up power and unlocked by the barrel recoil. The breech block 11 is spring-loaded by the recuperating spring 12 supported in the breech casing.

The cradle 3 includes an arm 13 to which is fixed, by means of a bolt 15, the outer casing 14 now merely constituting the slide bar of the breech casing. The bolt 15 slides, by means of a round guide piece 16, in a hole 17 of the arm 13, and is spring-loaded by the spring 18. A cap 19 rigidly connected with the bolt serves to loosen the bolt 15 from the outer casing 14, and consequently the casing 14 from the cradle 3. The casing 14 includes the trigger casing 20 containing a trigger of known design which need not be more particularly described here. The ammunition feed frame 21 is also rigidly connected with the trigger casing.

In the constructional example according to Figs. 1 and 4, ammunition is fed in belts, as shown in Figs. 3 and 4. The individual cartridges 22 are arranged in belt elements 23. The working of the belt feed is seen in greater detail in Figs. 3 and 4. A part 24 rigidly connected with the barrel and the breech casing, catches with a pin 25 into a corresponding recess of a lever 26. The lever 26 is rotatably seated on a pin 27 and catches with a finger-shaped projection 28 into the slot 29 of a slide 30. The slide 30 is displaceably fitted in the casing 14, i. e. in the ammunition feed frame 21 rigidly connected with it. The slide 30 actuates two feeding pawls 31 which move the belt one step forward after each round. A check pawl 32 is fitted in the ammunition feed frame 21.

3

The working of this known cartridge feeding device is briefly as follows:

At the release of each shot, the part 24 rigidly connected with the barrel and the breech casing moves in the direction indicated by the arrow (Fig. 4). Thereupon, the pin 25 swings the lever 23 round the axis 21, thus causing the slide 30, through the finger-shaped projection 28 guided in the slot 29, to move in the direction indicated by an arrow. This causes, through the action of the feeding pawls 31, the belt to move one cartridge forward.

Fig. 5 shows an ammunition magazine 33 inserted in known manner in the ammunition feed frame 21 fitted to the outer casing 14.

The constructional examples are merely schematically represented and described above only insofar as their essential parts are concerned. A fuller description is not needed, since the principle of the invention—characterized by the feature that the outer casing is now designed merely as top slide bar for the breech casing, and has fitted to it the trigger casing and the ammunition feed frame, suitable both for belt and magazine cartridge feed—can be applied in firearms of various designs. The same applies to the trigger, which does not call for any particular explanation either, since widely different designs can be used within the scope of the principle of the invention.

We claim:

1. In an automatic firearm, the combination of an outer casing in the form of a laterally open structure, and consisting essentially of an upper portion and a bottom cradle portion, a laterally accessible breech block casing movable axially within the outer casing and supported slidably on the cradle portion and sliding on the inner surface of the upper portion of the outer casing, a breech block slidable axially within the breech block casing, the breech casing and outer casing, and likewise the breech block and breech block casing having interfitting rectilinear guide elements whereby the breech block casing and the breech block move parallel to the longitudinal axis of the firearm for the full extent of their movements, trigger mechanism and a buffer

4

spring system therefor, both carried by the outer casing, and a cartridge feed frame likewise carried by said outer casing.

2. The combination as defined in claim 1, wherein the cartridge feed frame is constructed to receive a cartridge belt and is fitted on the trigger casing.

3. The combination as defined in claim 1, including a magazine positioned in the cartridge feed frame.

4. In an automatic firearm, the combination of an upper trackway and a bottom cradle of substantially flat construction and extending parallel to each other and provided with flat, rectilinear, parallel guideways extending in the axial direction, the trackway and cradle being spaced from and connected with each other in such manner that the space therebetween is accessible from both sides, said trackway and cradle thereby forming a skeleton outer casing, a breech block casing of substantially rectangular form and provided with track members sliding in said guideways, a breech block slidable axially within the breech casing, said breech and breech block casing being likewise provided with interfitting rectilinear guide elements whereby the breech block moves parallel to the longitudinal axis of the firearm for the full extent of its movement, trigger mechanism and a buffer spring system therefor, both carried by the outer casing, and a cartridge feed frame likewise carried by said outer casing.

HANNS LIPPERT.
ERWIN HEPPERLE.
